UNITED STATES PATENT OFFICE.

HENRY E. LOHMAN, OF RUSSELL, KANSAS.

DISK DRILL.

1,079,871.

Specification of Letters Patent. Patented Nov. 25, 1913.

Application filed July 3, 1913. Serial No. 777,204.

To all whom it may concern:

Be it known that I, HENRY E. LOHMAN, a citizen of the United States, residing at Russell, in the county of Russell and State of Kansas, have invented certain new and useful Improvements in Disk Drills, of which the following is a specification.

The present invention relates to a disk drill, and has for its object to provide a device of this character which is comparatively simple and inexpensive in its construction, and which embodies novel features of design whereby the ground is effectively opened up and the grain properly spread therein.

With this and other objects in view, the invention consists in certain novel combinations and arrangements of parts as will more fully appear as the description proceeds, the novel features thereof being pointed out in the appended claims.

For a full understanding of the invention, reference is to be had to the following description and accompanying drawing, in which:

Figure 1 is a side elevation of a grain drill constructed in accordance with the invention, portions being broken away and shown in section. Fig. 2 is a top plan view of the same. Fig. 3 is a vertical transverse sectional view on the line 3—3 of Fig. 1, and Fig. 4 is a similar view on the line 4—4 of Fig. 1, with the boot in an upright position.

Corresponding and like parts are referred to in the following description and indicated in all the views of the drawings by the same reference characters.

Specifically describing the present embodiment of the invention, the numeral 1 designates the beam which has the rear end 40 thereof deflected upwardly as indicated at 1^a, while the forward extremity thereof is provided with a clevis 2 or other suitable means for applying draft to the beam. At an intermediate point in the length thereof 45 the beam 1 is provided with a transverse opening within which a tubular bushing 3 is rigidly fitted, the ends of the bushing projecting laterally beyond opposite sides of the beam. A bearing sleeve 4 is journaled 50 within the tubular bushing 3, the said bearing sleeve being provided at one end thereof with a flat disk 5. As shown in the drawing the sleeve 4 is provided at one of its extremities with an outstanding flange 4^a to 55 which the disk 5 is riveted or otherwise rigidly connected. This bearing sleeve 4 may

be inserted into the bushing 3 from either side of the beam 1 so as to position the disk 5 upon that side of the beam which may be most expedient. A retaining bolt 6 extends 60 through the bearing sleeve 4, the head 6^a of the bolt engaging the end of the bearing sleeve to which the disk 5 is attached, while the opposite end of the bolt has a nut 7 threaded thereon, a washer 8 being interposed 65 between the nut and the ends of the bushing 3 and bearing sleeve 4. The end of the bolt 6 adjacent the head 6^a preferably has an angular or polygonal formation as indicated at 6^b for engagement with a corresponding socket in the bearing sleeve 4 so as to prevent rotation of the bolt 6 when placing the nut 7 in position or removing it therefrom.

In order to bring the shovel 10 approximately in alinement with the disk 5, the rear end of the beam 1 is offset laterally as indicated at 1^b. The boot 9 is applied to this laterally offset end of the beam 1 and has an extension 9^a at the lower end thereof to 80 which the shovel 10 is removably applied in some suitable manner, as by means of the bolt 11. A suitable hopper 12 may be applied to the upper end of the boot 9 if desired. The lower end of the boot 9 and 85 shovel 10 must be disposed immediately in rear of the disk 5 so that the shovel 10 will open up the slit formed in the ground by the disk 5, the seed being dropped through the boot 9 into the furrow or opening 90 formed in the ground by the combined action of the disk and shovel.

The boot 9 may be mounted upon the end of the stock in any suitable manner, although in the present instance it is shown 95 as pivotally connected to the rear end of the stock by means of a pivot bolt 13. The boot 9 can be swung laterally about the pivot bolt 13 so as to bring the point of the shovel 10 into exact alinement with the disk 5 and 100 proper adjustment thereby made.

Suitable means may be provided for locking the boot 9 against pivotal movement upon the bolt 13, and for this purpose an angle bracket 14 is shown as applied to the 105 rear end of the beam 1 at the top thereof. One flange of the angle bracket is bolted to the beam as shown at 15, while the opposite flange thereof is provided with a segmental slot 16 receiving a clamping bolt 17. This 110 bolt moves freely within the slot 16 when loosened, although after the boot has been

properly adjusted the said clamping screw 17 is tightened to lock the boot against movement.

Having thus described the invention, what I claim as new and desire to secure by Letters Patent, is:—

1. A disk drill including a beam having a transverse opening therein, a tubular bushing fitted within the opening, a sleeve 10 adapted to be journaled within the bushing, a disk at one end of the sleeve, the said disk being adapted to be positioned upon either side of the beam, a boot adjustably mounted upon the rear end of the beam, a shovel 15 carried by the boot, the said boot being adapted to be swung laterally to position the point of the shovel in alinement with the disk, and means for locking the boot in an adjusted position.
2. A disk drill including a beam having a transverse opening therein, a tubular 20

bushing mounted within the opening, a sleeve journaled within the bushing and adapted to be inserted into the bushing from either end thereof, a disk at one end of the sleeve, said disk being adapted to be positioned upon either side of the beam, means for retaining the sleeve within the bushing, a boot adjustably mounted upon the rear end of the beam so as to have a lateral 25 swinging movement, a shovel carried by the boot and adapted to have the point thereof swung into alinement with the disk, and means for locking the boot in an adjusted position. 30 35

In testimony whereof I affix my signature in presence of two witnesses.

HENRY E. LOHMAN.
